UNITED STATES PATENT OFFICE.

ROBERT D. BAKER, OF DETROIT, MICHIGAN.

METHOD OF GRADING ROADEDS FOR CONCRETE ROADS.

1,392,674.

Specification of Letters Patent.

Patented Oct. 4, 1921.

Application filed May 8, 1919. Serial No. 295,592.

To all whom it may concern:

Be it known that I, ROBERT D. BAKER, a citizen of the United States of America, residing at Detroit, in the county of Wayne 5 and State of Michigan, have invented certain new and useful Improvements in Methods of Grading Roadbeds for Concrete Roads, of which the following is a specification, reference being had therein to the accompanying drawings.

The invention relates to the art of constructing concrete roads and it is the object of the invention to facilitate the grading of the road bed so as to secure greater accuracy 15 and to avoid unequal density, tending to cause cracking of the cement when laid thereon.

In the present state of the art it is usual to perform the grading by road grading machines in which the blade or scraper is vertically adjustable and is under the control of an operator. It has been found in practice that it is practically impossible to accurately follow the grade in this way, and as 20 a consequence there are places which are too low and require subsequent filling. Such filled spots are seldom of exactly the same density as the undisturbed earth, so that after the cement is laid unequal settling will 25 often cause it to crack. Moreover, the establishment of even an approximate grade by this method requires skill on the part of the workmen, which increases the cost of the operation.

With my improved method highly accurate grade is obtained without particular skill on the part of the workmen, while removal of earth from below the grade is absolutely prevented. Furthermore, the operation can be performed more expeditiously 40 and when completed will leave a road bed of uniform density, affording equal support for the cement laid thereon.

In the drawings:

- 45 Figure 1 is a side elevation;
Fig. 2 is a cross-section;
Fig. 3 is a plan view.

The essential features of my improved method is the accurate placing of a gage extending longitudinally of the road bed and serving to limit the depth of removal of earth. Preferably such a gage or limiting device is placed on each side of the road bed and the grading machines are provided 50 with coöperating means extending across between said gages and limiting the depth of

the cutting blade or in other terms, the method consists in establishing means along and over the roadway and entirely extraneous thereto, which cause excavating means 60 used in conjunction therewith to traverse the roadway in planes parallel to a predetermined profile surface and, if desired, at such a distance below the surface of the ground as would insure substantially equal density 65 of the road bed.

As specifically shown, A are rail sections which are supported on chairs B, such chairs being preferably arranged at the joint between successive rails to form a coupling 70 connection therebetween and also located at intermediate points. The chairs B may be supported upon blocks C, and suitable vertical adjustment means is provided, such as the pivotal legs D, which may be spread at 75 different angles to raise or lower the rail. E is a grading machine of any suitable construction, being provided with a vertically adjustable cutting blade F mounted on a suitable carriage. The raising and lowering 80 of the blade is controlled by the operator through suitable means, such as the wheel Q, as is usual with machines of this type. H is a bar, preferably a tube, which is of sufficient length to extend across the 85 road bed and over the rails A. This bar is clamped to the vertically adjustable blade F in such a manner that when the opposite end portions of the bar come in contact with the rails A further downward movement of 90 the blade is prevented. On the other hand, the blade is freely adjustable on its wheeled frame when the bar H is above the rails.

In carrying out the method, the rails A are first positioned and connected to each 95 other and to the supporting stand B upon opposite sides of the road bed. The height is then adjusted by raising or lowering the chairs in conformity to the level established by the surveyor's stakes, but the upper face 100 of the rail is at a predetermined height above the desired grade. The bars H are then clamped to the graders E in such a manner that the lower or cutting edge of the blade F will be exactly on grade when 105 said bars H are resting on the upper faces of the rails. If the road bed is to be rounded, the bars H are of a similar curve and when working upon opposite sides of the road the bars H are adjusted laterally so 110 as to always maintain the overlap in relation to the rails A. When the apparatus is

adjusted as described, the work of removing the earth may proceed in the ordinary manner and without necessity of particular care on the part of the workmen, for it will be impossible for the blade to cut below the desired depth. On the other hand, if the ground is high, it may be removed by a series of cuts and the blade may be adjusted in relation to its supporting frame to facilitate this operation. With horse drawn graders the length of the cutting blade is generally very much less than the total width of the road bed, which necessitates lateral adjustment of the bars H for different lines of cut. This adjustment may, however, be easily performed by providing quick operating clamps for attaching the bar H to the blade, as indicated at J.

It will be understood that in setting the rails A they need only extend for a comparatively short section of the road and after this is brought to grade said rails may be shifted in position for the grading of another section.

25. What I claim as my invention is:—

1. The method of grading road beds for concrete pavement foundations which consists in establishing temporary gaging means along and over the roadway entirely extraneous thereto, the longitudinal and transverse guiding members of which are substantially coincident with the elements of a predetermined profile surface for the roadway, in placing thereon excavating means, the movements of which are limited and confined by such guides to planes parallel to the surface in surfacing the ground between the guides therewith.
2. The method of grading road beds for concrete pavement foundations which consists in establishing temporary gaging means along and over the roadway entirely extraneous thereto, having longitudinal and transverse guiding members which are adjustable to be brought into substantially coincident relation with the elements of a predetermined profile surface, in providing excavating means the movements of which are limited by such gaging means to planes parallel to the profile surface and in removing the earth along the roadway by such means.
3. The method of grading road beds for concrete pavement foundations which consists in establishing gaging means along and over the roadway and entirely extraneous thereto, having guiding means that are ad-

justable to be brought into substantial coincidence with the longitudinal and transverse elements of a predetermined profile surface for the roadway, in providing excavating means for working the roadway, that are controlled by the gaging means to traverse planes parallel to the profile surface and at any distance below the latter within the limits of the apparatus, and in removing the earth along the roadway by said means.

4. The method of grading road beds for concrete pavement foundations, which consists in establishing gage rails along the surface of the soil in the direction of the right of way at a desired height above the proposed grade and entirely extraneous to the roadway in mounting excavating mechanism upon the rails to move in planes parallel to a predetermined profile surface at the desired distance below the gage rails and in removing the superfluous dirt by these excavating means.

5. The method of grading road beds for concrete pavement foundations, which consists in placing gage rails along the proposed right of way on supports entirely outside the road bed which permit accurate adjustment of the rails in planes parallel to a predetermined profile surface, in placing transverse guiding members upon the rails lying parallel to the elements of the predetermined profile surface, in mounting excavating means upon the rails and transverse guides to traverse the surface of the ground in planes parallel to the predetermined profile surface and in removing the superfluous dirt by these excavating means.

6. The method of grading road beds for concrete pavement foundations, which consists in mounting sets of gage rails on the surface of the ground along the proposed right of way entirely outside the road bed, providing means for vertically adjusting the rails to lie in planes parallel to a predetermined profile surface, in mounting a transverse guiding member upon the rails to move in a plane parallel to the predetermined profile surface, in mounting excavating means upon the guiding rails and guide in such a manner that it traverses the road bed in planes parallel to the predetermined profile surface and in excavating the superfluous dirt by these excavating means.

In testimony whereof I affix my signature.

ROBERT D. BAKER.
